TRANSMITTER FOR TELEPHONY

Filed Oct. 4, 1926

Inventor:

Heinrich Küchenmeister.

UNITED STATES PATENT OFFICE

HEINRICH KÜCHENMEISTER, OF BERLIN, GERMANY

TRANSMITTER FOR TELEPHONY

Application filed October 4, 1926, Serial No. 139,338, and in Germany October 13, 1925.

It is known to increase the volume of sound in talking machines by arranging microphones one in back of the other whereby the same sound is reproduced with 5 in certain time intervals.

The object of this invention is an arrangement of apparatus which permits this idea to be applied to telephone transmitters.

The drawing illustrates diagrammatically 10 one form of the invention.

In the present instance, four transmitter microphones 1 to 4 having individual diaphragms are arranged before the person using the telephone in succession to one another, preferably as the accompanying 15 drawing shows, in a single trumpet 5 say 80 cms. long. The microphones 1 and 4 are arranged at opposite ends of the trumpet while the microphones 2 and 3 are disposed 20 at intermediate points therein. It is advantageous to adjust the sensitivity, that is the transmitting strength of the individual microphones in such a way that the resulting impulses are equally strong in spite of the 25 varying distances of the microphones from the source of sound, for example the mouth.

The time intervals of less than one hundredth of a second resulting from the separation is sufficient to produce that multiple 30 overlapping of the sound impulses which is received by the ear as an enhanced fulness of the tones. It is thus possible to obtain good reception in spite of unfavourable conditions particularly in long distance telephone lines.

The reception can be notably improved by using two transmission lines instead of one, the second line being led to a second receiver. Thus, when a series of four microphones are employed, as herein shown, 40 two of them, for instance the microphones 1 and 3, are connected to one transmission line 6 and the microphones 2 and 4 are joined to the line 7 and each line is provided 45 with an individual receiver, conventionally shown at 8.

What I claim is:—

1. In a telephone transmitter, a single trumpet and groups of microphones supported within said trumpet in aligned rela-

tion one behind another and widely apart from each other.

2. In a telephone transmitter, a single trumpet and groups of microphones supported in the middle of said trumpet in aligned relation one behind another and widely apart from each other for the purpose of creating electrical currents of different phases in the connecting wires, each of said microphones having an individual diaphragm.

In testimony whereof I have signed my name to this specification.

HEINRICH KÜCHENMEISTER.
